HEATING APPARATUS

Henry J. De N. McCollum, Evanston, Ill.

Application August 11, 1939, Serial No. 289,575

3 Claims. (Cl. 126—110)

My invention relates generally to heating apparatus, and more particularly to improvements in gaseous or vaporized liquid fuel burners combined with heat exchange means.

It is an object of my invention to provide an improved unit type heater using a gaseous vaporizable liquid as a source of fuel, in which combustion takes place in a rotating unit which at the same time serves as a heat exchange device.

A further object is to provide an improved burner for gaseous and liquid fuels.

A further object is to provide an improved heat exchange apparatus of efficient construction.

Other objects will appear from the following description, reference being had to the accompanying drawings, in which:

Figure 1 is a front elevation of the apparatus, portions thereof being broken away to show concealed parts in section;

Figure 2 is an enlarged vertical sectional view taken on the line 2—2 of Figure 1;

Figure 3 is a vertical sectional view taken on the line 3—3 of Figure 2;

Figure 4 is a fragmentary horizontal sectional view taken on the line 4—4 of Figure 1;

Figure 5 is a fragmentary sectional view taken on the line 5—5 of Figure 2, but shown to a slightly reduced scale;

Figure 6 is a fragmentary sectional view taken on the line 6—6 of Figure 1, showing a means for supporting the unit;

Figure 7 is a wiring diagram showing an electric circuit which may be used in conjunction with the unit.

Various types of unit heaters employing gaseous or a vaporized liquid fuel have been proposed and used in the past, but for the most part such heaters have been of relatively large size compared to the amount of heat produced. This was due mainly to the fact that in most instances the natural convection was relied upon to convey heat from the apparatus, or in such instances where fans were utilized to promote the circulation of air past or through the unit, a rather bulky radiator was necessarily employed in order to transfer the heat from the gases of combustion to the air circulated through the unit.

In the present invention, the heat which is generated by the combustion of fuel is transmitted directly to the blades of the fan used to circulate the air through the unit by making the fan blades hollow and causing the gases of combustion to flow through the hollow blades. By virtue of the high speed of the fan blades relative to the air, the rate of heat transfer from the gases of com-

bustion to the air is very rapid and efficient. Furthermore, the gases of combustion flowing radially outwardly through the fan blades are centrifugally accelerated, and thus cause a partial vacuum at the point at which the fuel and air are supplied, thereby promoting the rapid circulation of the gases of combustion through the unit, and consequently increasing the amount of heat which may be delivered by a unit of a given size.

Referring to Fig. 1, the heating unit comprising a casing 10 which is channel shaped in cross section (as best shown in Fig. 2) and which is of increasing depth in the clockwise direction (Fig. 1) so as to provide a channel 12 of gradually increasing cross sectional area, the channel terminating in a tangential outlet projection 14 which may be formed integrally with the casing 10. The casing 10 may be supported in any suitable manner, depending upon the particular use to which the unit may be put, and is illustrated as being clamped to pipes 16 and 18, the latter being clamped in split blocks 20 (Fig. 6) which are secured in the split ends of tubular standards 22 by means of cap screws 24. The pipes 16 and 18 are illustrated as being secured to the housing 10 by brackets 26 which are provided with set screws 28, so that the angle of the plane of the housing 10 with respect to the standards 22 may be adjusted at will.

As best shown in Figs. 1, 3 and 4, the pipe 16 is connected to a source of gaseous fuel by a hose 30, and is provided with a nozzle 32 which is held in position at the inner end of the pipe 16 by an adjustable set screw 34 which is clamped in position by a lock nut 36. The inner end of the set screw 34 projects into the passageway through the nozzle 32 and by suitable adjustment may be made to restrict this passageway and thereby control the rate of flow of gaseous fuel through the nozzle.

A mixing chamber 38 of generally cylindrical conformation is formed in a casting 40 which is supported by the pipes 16 and 18, the ends of these pipes being suitably located in sockets formed in the casting 40 by set screws 42. It will be noted that the pipe 18 projects into a closed end socket, whereas the pipe 16 is held in a cylindrical bore which communicates with the mixing chamber 38. The forward end of the mixing chamber is provided with a plurality of openings 44 which register wholly or to an adjustable extent with corresponding openings 46 formed in a disc 48 which is rotatable upon a central stud 50 threaded in the front wall of the casting 40.

The amount of atmospheric air admitted

through the openings 44 and 46 may thus be adjusted by rotating the disc 48 on the stud 50, causing the openings 44 and 46 to register to the desired extent. A disc 52 is secured to the inner end of the stud 50 and is of slightly greater diameter than a hollow cylindrical boss 54 formed integrally with the casting 40. The width of the space between the disc 52 and the end of the boss 54 may be adjusted by rotation of the stud 50, and may be locked in adjusted position by means of a nut 55.

Within the casting 40, beneath the mixing chamber 38, is a bore 56 (Fig. 2) in which an igniter shell 58 of generally tubular shape is secured. This casing forms a support for a coil of high resistance wire 60, the inner end of which is welded to the igniter shell 58, and the other end of which is welded to a terminal stud 62 which is insulated from the shell by suitable insulating washers and an insulating sleeve, which is held in place by a nut 64, and to which a wire terminal lug 66 is clamped by means of a nut 68. The inner surface of the shell 58 is preferably finished in dull black, by suitable plating or an oxidizing process.

An electric motor 70 is secured to a mounting plate 72, the plate being supported by a plurality of arms 74 which are welded, respectively, to the plate 72 and to an annular ring 76 which is secured to the channel shaped housing 10. A hollow hub 78 is secured to a flanged bushing 80 which in turn is non-rotatably secured to the rotating shaft 82 of the motor 70 by a set screw 84. The hub 78 has a plurality of hollow fan blades 86 projecting radially therefrom, the blades fitting into suitably shaped openings formed in the cylindrical flange of the hub 78 and being brazed or welded thereto. The outer ends of the hollow or tubular blades 86 are fitted into suitable apertures formed in a channel shaped felly 88, being brazed or welded thereto. The felly 88 fits closely within the channel shaped housing 10, the clearance between the sides of the felly 88 and the side walls of the channel housing 10 being made as small as is compatible with the free rotation of the felly 88 within the housing 10.

Similarly, the clearance between the forward edge portion of the flange 79 of the hub 78, and the casting 40 is made as small as possible without destroying the free running fit between these parts.

The outlet 14 of the housing 10 has a pipe or other suitable conduit 90 connected thereto, this conduit leading to a flue which, due to natural convection, will draw the products of combustion from the outlet 14, or the conduit may be provided with a suction blower in order to create a partial vacuum at the outlet 14.

As illustrated diagrammatically in Fig. 7, the supply of energizing current to the apparatus is controlled by a two pole switch 92 connected to a suitable source of current. Closure of the switch 92 completes a circuit to the electric motor 70 and also to the winding of a solenoid 94 which is connected in parallel with the motor 70. The plunger of the solenoid 94 is connected to a valve 96 which is normally held in closed position by a spring 98. The valve 96 controls the flow of gaseous fuel through a conduit 100 to which the hose 30 is connected.

A bimetal thermostatic element 102 is suitably mounted upon the casing 10 and is arranged when at atmospheric temperature, to complete a circuit to the igniter coil 60. As soon as the

heater commences operation and the casing 10 is thus raised in temperature, the thermostatic element 102 will flex so as to break the circuit to the igniter 60. If desired, the operation of the switch 92 may be controlled by a room thermostat so that the heater is rendered operative whenever the temperature of the room drops below a predetermined value.

To cause the heater to commence operation, it is necessary merely to close the switch 92 either manually or by means of a thermostat control relay, whereupon the motor 70 will commence operating and the valve 96 opened to permit the flow of a supply of gaseous fuel to the mixing chamber 38.

The coil of the igniter 60 may be made of relatively fine wire so as to heat up rapidly. As a result the igniter will be at ignition temperature shortly after the flow of gas to the mixing chamber 38 commences. The gas flowing into the combustion chamber will, of course, be mixed with air flowing through the openings 44, 46 formed at the front of the combustion chamber so as to form a combustible mixture which may readily be ignited by the igniter.

A partial vacuum will be formed due to the rotation of the hollow fan blade assembly which will act as a centrifugal blower to draw the products of combustion from the hub 78 and eject the gases of combustion into the space between the felly 88 and the channel shaped housing 10, whereupon these gases will flow outwardly through the outlet 14 and conduit 90 either to a flue of sufficient height to cause the necessary draft, or through a suction blower.

As the heated gases flow radially outwardly through the hollow blades 86, the latter will of course be heated to a high temperature, and since the fan blade assembly is rotated at high speed, the rate of heat conduction from the outer surfaces of the fan blades will be very rapid, and the heat transfer correspondingly efficient.

The rate of production of heat may, of course, be readily controlled by adjustment of the screw 34 to limit the size of the opening through which the gas is supplied to the mixing chamber 38, and the amount of air supplied may, of course, be controlled by adjustment of the position of the disc 44. Likewise, the annular opening between the plate 52 and the flange 54 may be adjusted in size by turning the stud 50 to a position which results in combustion at the desired rate.

The adjustments are preferably made in a manner such that substantially complete combustion will take place within the hollow hub 78 which forms the combustion chamber. Since the combustion chamber is at sub-atmospheric pressure, and since the space between the casing 10 and felly 88 is likewise under sub-atmospheric pressure, there is no danger of the escape of the gaseous products of combustion into the room in which the heater is located, and there will, of course, be some infiltration of atmospheric air to the system through these apertures.

The infiltration of air into the combustion chamber within the hub 78 through the annular space between the flange 79 and the casting 40 may be advantageously used to assure complete combustion within the combustion chamber and be considered as part of the air supply for the proper combustion of the fuel. Infiltration of air between the felly 88 and the channel shaped housing 10 does not have any material effect except as it may add to the volume of gas which is to be conveyed through the con-

duit 90 and to be handled by the blower or stack.

The unit may be made very small relative to its heat production capacity, due to the very efficient heat transfer which is obtained, and due to the fact that the flow of the gases of combustion through the apparatus may be at a very rapid rate.

It will be understood by those skilled in the art that although I have disclosed but a single embodiment of my invention, numerous modifications and variations thereof may readily be made without departing from the underlying principle thereof. I therefore desire, by the following claims, to include within the scope of my invention all such varied and modified forms of my invention whereby substantially the results of my invention may be obtained by substantially the same or similar means.

I claim:

1. In a rotating heat radiator comprising a motor driven fan having a combustion chamber in the hub thereof into which a combustible mixture is drawn by the suction created by rotation of said fan, the combination comprising a fuel and air mixing chamber projecting into said combustion chamber, a fuel inlet for said mixing chamber, air inlets for said mixing chamber, means for adjusting the fuel and air intake to said mixing chamber and the flow of combustible mixture to said combustion chamber operable independently of each other, said means including an axially extending stud in said mixing chamber having an apertured plate threaded on its outer end and a disc secured on its inner end, said apertured plate being rotatable on said stud to vary the registration between the apertures therein and said air inlets for regulating the flow of air to said mixing chamber, and said stud being rotatable independently of rotation of said apertured plate to vary the opening between the disc secured thereon and the outlet of said mixing chamber, thereby regulating the flow of combustible mixture to said combustion chamber.

2. In a rotating heat radiator comprising a motor driven fan having a combustion chamber in the hub thereof, and a support for said heater, the combination comprising a fuel and air mixing chamber carried on said support and communi-

cating with said combustion chamber, an adjustable fuel inlet for said mixing chamber, inlets in said mixing chamber for the admission of air thereto, a longitudinally extending stud in said mixing chamber, an apertured plate threaded on the outer end of said stud, said plate being adjustable on said stud to vary the registration of the apertures therein and said air inlets for regulating the flow of air to said mixing chamber, a plate positioned over the outlet of said mixing chamber and secured to the inner end of said stud, said stud being rotatable independently of rotation of said apertured plate to vary the opening between the plate secured thereon and the outlet of said mixing chamber, thereby regulating the flow of combustible mixture to said combustion chamber when the fan is rotating.

3. In a rotating heat radiator comprising a motor driven fan having a combustion chamber in the hub thereof with an open front end and a tubular support for said heater, the combination comprising means secured on said support for closing the open end of said combustion chamber, said means including an igniter and a fuel and air mixing chamber projecting into said combustion chamber, said mixing chamber having an apertured front end for admitting air to said mixing chamber and an open back end, a fuel inlet for said mixing chamber formed by said tubular support, means for adjusting the fuel admitted to said mixing chamber, an axially extending stud threaded in the front end of said mixing chamber, an apertured plate rotatably mounted on the outer end of stud, said plate being adjustable to vary the registration of the apertures therein and the apertures in the front of said mixing chamber for regulating the flow of air to said mixing chamber, a plate positioned over the inner end of said mixing chamber and secured to the inner end of said stud, said stud being rotatable independently of rotation of said apertured plate to vary the opening between said plate and mixing chamber thereby regulating the volume of combustible mixture drawn from said mixing chamber by suction in said combustion chamber resulting from rotation of said fan and means for locking said plates in adjusted position.

HENRY J. DE N. McCOLLUM.
